UNITED STATES PATENT OFFICE.

JAY M. JOHNSON, OF CHICAGO, ILLINOIS.

WEIGHT-MOTOR.

1,359,994.

Specification of Letters Patent. Patented Nov. 23, 1920.

Application filed April 14, 1917. Serial No. 162,045.

To all whom it may concern:

Be it known that I, JAY M. JOHNSON, a citizen of the United States, and a resident of the city of Chicago, in the county of 5 Cook and State of Illinois, have invented certain new and useful Improvements in Weight-Motors; and I do hereby declare that the following is a full, clear, and exact description of the same, reference being had 10 to the accompanying drawings, and to the numerals of reference marked thereon, which form a part of this specification.

This invention relates to an improved driving mechanism particularly adapted for 15 use on phonographs, talking machines, and other similar devices wherein an even source and application of power is desired. This invention contemplates the use of gravity as a source of power, and mechanisms are 20 provided for utilizing the force of gravity acting on a weight member for the purpose intended.

It is an object therefore of this invention to construct a weight motor wherein the 25 force of gravity is utilized as an element of the source of power for the mechanism, and with means for automatically shifting the mechanism subject to the force of gravity to maintain its position to be acted upon by 30 the force of gravity whereby the force or energy effect thereof may be utilized.

It is also an object of this invention to construct a driving mechanism wherein a weighted member is subject to gravity to 35 impose a force effect upon the driving mechanism.

It is furthermore an object of this invention to construct a driving mechanism utilizing a weight member susceptible to the force 40 of gravity and provided with means power driven and operable to elevate or maintain said weight member elevated whereby the force effect thereof upon the driving mechanism is continuously manifested.

45 Other and further important objects of my invention will be evident from the disclosure in the drawings and specification.

The invention (in a preferred form) is illustrated in the drawings and hereinafter 50 more fully described.

On the drawings:

Figure 1 is a central vertical section with parts omitted taken through a talking machine equipped with driving mechanisms embodying the principles of my invention, and 55 with the operation shown in dotted lines.

Fig. 2 is an enlarged side elevation of the mechanism shown in Fig. 1, with the operation illustrated in dotted lines.

Fig. 3 is a top plan view of the movable 60 gravity mechanism.

Fig. 4 is a sectional detail on line 4—4 of Fig. 1.

Fig. 5 is a fragmentary front view of a mechanism embodying the principles of my 65 invention, adapted to a machine.

Fig. 6 is an enlarged view thereof with parts in elevation, and parts in section.

Fig. 7 is a sectional detail taken on line 70 7—7 of Fig. 5.

Fig. 8 is a fragmentary bottom plan view of the mechanisms suspended beneath the top plate or wall of the machine.

As shown on the drawings:

The reference numeral 1, indicates the 75 cabinet or casing of a talking machine or phonograph of any conventional type, provided with a horizontal partition wall 2, in the upper portion thereof, and with a record carrying disk 3, rotatably journaled there- 80 above in a usual and well known manner. Said record carrying disk is supported on and driven by an axial shaft 4, which extends downwardly therefrom through the wall 2, and is journaled in a bracket 5, se- 85 cured therebeneath. Journaled horizontally in bearings 6, is a horizontal shaft 7, of a transmission mechanism equipped with a centrifugal speed governing mechanism 8, and having a worm 9, which meshes with 90 a worm gear 9^a on the shaft 4. This portion of the driving mechanism is, however, old and forms no part of the present invention, and hence further details thereof are not entered into. Also secured upon the 95 shaft 7, is a sprocket wheel 10, and trained thereabout is a continuous chain 11.

A gravity member consisting of a block 12, is suspended from one run or flight of the chain 11, due to the fact that said chain 100 is trained around a large sprocket wheel 13, and over a small sprocket wheel 14, which are secured upon shafts 15 and 16, re- 105 spectively, journaled in center bearings 17, mounted on the upper surface of said block 12. A worm wheel 18, is secured upon the shafts 15, and meshing therewith is a worm shaft 19, forming the armature shaft of a motor 20, mounted on the top surface of said block member 12.

110 Mounted on one side of the cabinet 1, on the interior thereof, is a switch comprising

an insulating block 21, with terminals 22 and 23, thereon, which are in electrical circuit with any source of E. M. F. and with said motor 20. Pivoted upon said switch block 21, co-axial with the terminal 22, and in circuit therewith, is a long U-shaped lever 24, and connected centrally beyond the pivot center thereof is a tension spring 25, which is connected to a fixed point on the switch block 21, acting to hold said lever in either one of its possible adjusted positions beyond dead center. One stop pin 26, is provided on the upper portion of the switch block 21, to limit the movement of said lever 24, in one direction, and another stop pin 27, is provided on the lower portion of said switch block and in circuit with the terminal 23, to limit the movement of said lever to its other position, and when the lever moves into contact with the stop pin 27 it establishes a circuit between the terminals 22 and 23. A pin extension 28, is provided on one side of the block member 12, for the purpose of operating said switch lever 24, in a manner hereinafter described.

In the modified form of device illustrated in Figs. 5 to 8, inclusive, instead of the sprocket wheel 10, on said shaft 7, I have shown a worm gear 29, and with a bearing bracket 30, fitted on said shaft and receiving therein one end of a vertical worm shaft 31, which is slidable upwardly therethrough and meshes with said worm wheel 29. Secured to and depending from the wall 2, are guide rods 32, and slidably mounted thereon is a gravity block member 33.

Mounted upon the block member 33, is a motor 34, provided with a worm 35, meshing with a worm wheel 36, which is secured 40 upon the worm shaft 31. As clearly shown in Fig. 6, the lower end of said worm shaft 31, extends rotatably through the block 33, and is provided with collars 37 and 38, respectively, recessed thereinto to retain said block supported thereon.

The operation is as follows:

In the form of mechanism illustrated in Figs. 1 to 4, inclusive, the weight block 12, is supported upon the chain 11, from the sprocket wheel 10, and, in moving downwardly under the influence of gravity, rotates said sprocket wheel 10, to drive the record carrying disk 3, and of course, the speed of rotation of the shaft 7, on which the sprocket wheel 10, is mounted, is controlled by the governing mechanism 8. At this time, of course, the sprocket wheel 13, around which said chain 11, is trained on the weight block 12, is stationary, and is so held by the worm shaft 19, which forms an irreversible driving connection from the motor 20, to the shaft 15, on which said sprocket wheel is secured. When the weight block 12, has reached its lower limit of 65 movement such as that shown in dotted lines

in Fig. 1, the pin extension 28, thereon, strikes the U-shaped switch lever 24, swinging the same slightly past dead center, and the movement thereof is continued by the spring 25, which thereby swings said lever 75 24, into contact with the pin 27, establishing a circuit to the motor 20, by closure of the circuit between the terminals 22 and 23, on the switch block. When the motor 20, is thus caused to operate, the shaft 15, is 80 driven thereby, and likewise its sprocket wheel 13, thereby causing the weight block 12, to be elevated on the chain 11, even though the chain 11, is still traveling around and rotating the sprocket wheel 10. This 85 is due to the fact that the rotation of the sprocket wheel 13, takes place at a higher speed than that of the sprocket wheel 10, the speed of which is governor controlled. When the weight block 12, has moved into 90 its upper limiting position, the pin 28, thereon, strikes the switch lever 24, swinging the same past dead center position and the movement is continued into the full line position shown in Fig. 1, so that contact 95 with the pin 27, is broken, the circuit to the motor 20, is opened, and the motor then ceases operation. The operation then again continues through the cycle described providing a continuous drive to the record disk 3. Of course, by opening the motor circuit by any suitable switch (not shown), the mechanisms are permitted to come to rest with the weight block 12, in its lowered position.

In the type of mechanism illustrated in Figs. 5 to 8, inclusive, the weight member 33, is supported upon a vertical worm shaft 31, which is journaled therethrough and which meshes with a worm wheel 29, on the 105 governor shaft 7, of the mechanism. The gravity effect of the weight member 33, tends to rotate the worm wheel 29, due to engagement of the worm shaft 31, therewith. The motor 34, is caused to operate 110 as before described when pin 28 operates switch 24, thereby rotating the worm shaft 31, in a direction to elevate the same together with the weight member 33, and mechanism supported thereon.

I am aware that various details of construction may be varied through a wide range without departing from the principles of this invention, and I therefore do not purpose limiting the patent granted 120 otherwise than necessitated by the prior art.

I claim as my invention:

1. A device of the class described comprising a sprocket wheel, a transmission mechanism driven thereby, a weight, a frame mounted on the weight, a pair of sprocket wheels journaled in the frame adjacent each other and in substantially the same plane, a sprocket chain engaged over the first-mentioned sprocket wheel and un- 130

der one and over the other of the pair of sprocket wheels on the weight, said sprocket chain being of sufficient length to permit downward movement of the weight, and 5 means whereby the sprocket wheels on the weight are prevented from rotating during the downward movement of the weight.

2. A device of the class described comprising a sprocket wheel, a transmission 10 mechanism driven thereby, a weight, a pair of sprocket wheels journaled on the weight adjacent each other and in substantially the same plane, and a sprocket chain engaged over the first sprocket wheel and under one 15 and over the other of the pair of sprocket wheels on the weight, said sprocket chain

being of sufficient length to permit downward movement of the weight, a mechanism for rotating one of the sprocket wheels on the weight to elevate the weight before its 20 gravitational power is exhausted, and means associated with said mechanism whereby said sprocket wheel is prevented from rotating during the downward movement of the weight.

In testimony whereof I have hereunto subscribed my name in the presence of two subscribing witnesses.

JAY M. JOHNSON.
